CLAIM

We claim the ornamental design for a smart watch, as shown and described.

DESCRIPTION

FIG. 1 is a front perspective view of a smart watch showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a rear perspective view thereof;
FIG. 9 is an enlarged cross-sectional view of the portion encircled in FIG. 4, when taken from line 9-9 of FIG. 7; and,
FIG. 10 is an enlarged cross-sectional view of the portion encircled in FIG. 6, when taken from line 10-10 of FIG. 4. The short dash-dot broken lines in the figures show portions of the smart watch which form no part of the claimed design.

The dot-dot-dot broken lines encircling portions of the claimed design that are illustrated in cross section form no part of the claimed design.
